(57) **CLAIM**

The ornamental design for a faceted glass cube jewelry strand, as shown and described.

DESCRIPTION

FIG. 1 is a perspective view of a faceted glass cube jewelry strand, showing a first embodiment of our new design; FIG. 2 is a perspective view thereof in a straightened configuration, showing an alternative position of use with fewer exemplary faceted cubes;

FIG. 3 is a front elevational view of FIG. 2, the rear elevational view being a mirror image thereof;

FIG. 4 is a top plan view of FIG. 2, the bottom plan view being a mirror image thereof;

FIG. 5 is a left-side elevational view of FIG. 2;

FIG. 6 is a right-side elevational view of FIG. 2;

FIG. 7 is a perspective view of a second embodiment thereof;

FIG. 8 is a perspective view thereof in a straightened configuration, showing an alternative position of use with fewer exemplary faceted cubes;

FIG. 9 is a front elevational view of FIG. 8, the rear elevational view being a mirror image thereof;

FIG. 10 is a top plan view of FIG. 8, the bottom plan view being a mirror image thereof;

FIG. 11 is a left-side elevational view of FIG. 8; and,

FIG. 12 is a right-side elevational view of FIG. 8.

The broken lines are shown for the purpose of illustrating both parts of the article as well as exemplary environmental subject matter. None of the broken lines form part of the claimed design. The broken away symbols in the drawings indicate that any portion of the article beyond what is shown forms no part of the claimed design.
